BRIEFCASE WITH DETACHABLE PURSE

Barbara Jean Dipadova, 509 E. Buckthorn,
Inglewood, Calif. 90301

Filed Nov. 3, 1971, Ser. No. 195,530

Term of patent 7 years

Int. Cl. D3—01

U.S. Cl. D87—5 B

FIG. 1.

FIG. 2.

FIG. 3.

FIG. 4.

FIG. 1 is a perspective view of a briefcase with detachable purse showing my new design;

FIG. 2 is a front elevational view thereof;

FIG. 3 is a side elevational view thereof, the opposite side being identical in appearance, and

FIG. 4 is a top plan view thereof.

I claim:

The ornamental design for a briefcase with detachable purse, substantially as shown and described.
